FIRE ALARM

Adolf K. Helmersen, Astoria, Oreg.

Refiled for abandoned application Serial No. 23,491, May 25, 1935. This application December 7, 1937, Serial No. 178,603

4 Claims. (Cl. 200—140)

This is a substitute application for applicant's abandoned application, Ser. No. 23,491, filed May 25, 1935.

This invention relates to an alarm device and more particularly to a device of this character especially adapted to be set into operation when the heat of the room or the like is caused to rise, as for example, because of fire, above a predetermined temperature for sounding an electrically operable signal device.

The invention together with its objects and advantages will be best understood from a study of the following description taken in connection with the accompanying drawings wherein:

15 Figure 1 is a wire diagram.

Figure 2 is a side elevational view of a thermal element embodying the features of the present invention.

20 Figure 3 is an end elevational view of the thermal element.

Figure 4 is a fragmentary sectional view showing the mounting for a rocker arm.

Figure 5 is a plan view of a spring.

25 Figure 6 is a sectional view through the thermal element.

Figure 7 is an end elevational view of the thermal element with certain parts removed.

Figure 8 is a plan view of the rocker arm.

In accordance with the present invention the 30 alarm consists broadly of a thermal element indicated generally by the reference numeral 10 and wired in circuit as shown in Figure 1 with a transformer 11 and an electrically operable signal element in the present instance a bell 12. It will

35 thus be seen that in response to a rise in temperature beyond a predetermined degree, the thermal element 10 will operate to close a switch indicated generally by the reference numeral 13 that is also arranged in the aforementioned circuit for

40 closing said circuit through the signal 12 for sounding the latter.

The improved thermal element 10 comprises a sealed casing 14 of suitable material in which is confined a suitable liquid 15. The casing 14 is 45 substantially oval in end elevation and in the end thereof is formed for the reception of plates 16 of insulating material as best shown in Figure 6. These plates 16 have depending end portions 16a forming legs for supporting the receptacle 14 above a supporting surface as also clearly suggested in Figure 2.

50 A substantially U-shaped bar 17 of conductive material has the ends thereof secured to the plates 16 through the medium of an elongated bolt 18 that also serves as a binding post. The

bolt 18 extends through the casing 14 and is enclosed within a tube 19 of metal extending between the end walls of the case 14 and lined with insulating material 20 as also shown in Figure 6. On the threaded end of the bolt 18 is a binding 5 nut 21.

The container 14 is of conductive material and is provided at one end with a binding post 22 as shown in Figure 1. Also, on the top thereof the sealed container 14 is provided with a fixed contact 23 provided for the switch 13. The movable contact of the switch is indicated by the reference numeral 24 and is provided on one end of a rocker arm 25. The contact 24 operates through a suitable opening 26 provided therefore in the 15 member 17.

The rocker arm 25 has a reduced portion pivoted as at 25a between the upstanding arms of a bifurcated post 28 that is formed with an integral pin 29 anchored within a suitable opening 20 provided therefore, in the member 17. The pin 29 also extends through an opening in one end of a spring 30 for anchoring this spring, the latter being curved as shown in Figure 6 and engaging the fork end of the arm 25 as shown. 25

Threaded into the member 17 is a post 31 on which is threaded the hub of a suitably graduated dial 32 secured at the desired adjustment through the medium of a lock nut 33. The hub of the dial 32 is provided with a shoulder against which the 30 heads 34 provided on the arms of the fork end 27 of arm 25 engage, which end of the arm straddles the hub of the dial 32 in a manner clearly suggested in Figure 2. It will thus be seen that by adjusting the dial 32 axially of the post 31 contact 35 40 may be placed in the desired spaced relation to the contact 23 so that the contact 23 will engage the contact 24 for completing the circuit only after a predetermined temperature has been exceeded.

As is obvious, and as shown in Figure 1 the binding posts 18 and 22 are provided for connecting the wires of the circuit to the device 10 for so arranging said device and switch 13 in the circuit that a closing of the switch 13 will complete the circuit to the bell 12 for setting the latter in operation.

As thought to be apparent the switch 13 is 45 adjusted so as to be closed at a predetermined temperature by properly adjusting the dial 32 axially of its post 31. When the temperature rises above a predetermined amount the casing 14 will be so effected by the heat as to expand sufficiently to engage contact 23 with contact 50 55

24 for closing the circuit and thereby sounding the signal 12.

It will be understood that the apparatus may be used either with a battery circuit or with the 5 usual house circuit.

Having thus described the invention, what is claimed as new is:—

1. In a device of the character described, an elongated expandible container of conductive 10 material and of oval shape in cross section and having a peripheral wall and end walls spaced inwardly from the respective opposite ends of the peripheral wall together with an insulated tube extending between said end walls centrally of the 15 container, supporting plates of insulating material for said container and having portions fitting within the ends of the peripheral wall of said container, a substantially U-shaped member having legs bearing against and spaced from the ends 20 of the container by said plates, said legs and plates being provided with openings alining with one another and with said tube, a bolt extending through the openings and said tube for securing said U-shaped member to the container, said 25 bolt adapted to serve as a binding post, a contact member mounted on the peripheral wall of said casing, and a contact member mounted on said U-shaped member and adapted to be engaged by the first named contact upon an expansion 30 of said casing, and a volatile liquid confined within said casing for expanding the latter when subjected to excessive heat.

2. In a thermal electric alarm, the combination of a thermic shell of oval shape in cross section and having a binding post extending there- 35 through and insulated therefrom, a substantially U-shaped member receiving between the legs thereof said shell and having openings in the legs thereof for receiving said post whereby said 40 shell and U-shaped member are secured in as- sembled relation, insulation plates spacing the legs of the U-shaped member from the shell, a contact member on one of the wider sides of said shell, a post rising from said U-shaped mem- 45 ber at the closed end of the U, a rocker arm piv- oltally mounted on said post and having a con- tact on one end thereof operating through an opening in the closed end of the U-shaped mem- ber and in substantial alinement with the first 50 named contact for cooperation therewith to com- plete a circuit, a spring anchored to the U- shaped member by said post and having an end bearing against the rocker arm to rotate the same in one direction, and means mounted on said U-

shaped member and engageable with said rocker arm for adjusting the latter in opposition to said spring.

3. In a thermal electric alarm, the combination of a thermic shell of oval shape in cross section and having a binding post extending therethrough and insulated therefrom, a sub- stantially U-shaped member receiving between the legs thereof said shell and having openings in the legs thereof for receiving said post whereby 10 said shell and U-shaped member are secured in assembled relation, insulation plates spacing the legs of the U-shaped member from the shell, a contact member on one of the wider sides of said shell, a post rising from said U-shaped member 15 at the closed end of the U, a rocker arm pivotally mounted on said post and having a contact on one end thereof operating through an opening in the closed end of the U-shaped member and in substantial alinement with the first named con- 20 tact for cooperation therewith to complete a cir- circuit, a spring anchored to the U-shaped member by said post and having an end bearing against the rocker arm to rotate the same in one direc- 25 tion, means mounted on said U-shaped member and engageable with said rocker arm for ad- justing the latter in opposition to said spring, and said means including a threaded post ex- 30 tends from the closed end of the U-shaped mem- ber, a dial having a hub threadedly engaged with the last named post, and said hub having a shoulder engaging the end of the rocker arm remote from the contact carried by said rocker arm for limiting rocking movement of said arm in one direction. 35

4. In a device of the character described, a thermic shell of oval shape in cross section and having a contact on one of its wider sides, a con- tact and indicator assembly arranged in the path 40 of the first named contact, and means for mount- ing said combined contact and indicator assem- bly on said shell including a substantially U- shaped member between the legs of which said shell is disposed, insulation plates spacing the legs from the ends of the shell, and an elon- 45 gated binding post extending through the legs of the U-shaped member and said shell for secur- ing the U-shaped member to the shell, said shell having arranged internally therein, a longitu- dinally extending tube, and a sleeve of insulat- 50 ing material lining said tube and within which the binding post is positioned.

ADOLF K. HELMERSEN.
